UNITED STATES PATENT OFFICE.

JOSEPH LESHER, OF VICTOR, COLORADO.

DESIGN FOR A SILVER SOUVENIR-MEDAL.

SPECIFICATION forming part of Design No. 34,359, dated April 16, 1901.

Application filed February 14, 1901. Serial No. 47,381. Term of patent 7 years.

To all whom it may concern:

Be it known that I, JOSEPH LESHER, a citizen of the United States, residing at Victor, in the county of Teller and State of Colorado, have invented and produced a new and original Design for a Silver Souvenir-Medal, of which the following is a specification.

My invention relates to a new and original design for a silver souvenir-medal, and is illustrated in the accompanying drawings, in which—

Figure 1 is a view of one side of the souvenir-medal, and Fig. 2 a view of the reverse or obverse side.

15 My design consists of a silver souvenir-medal having the features hereinafter described, reference being made to the accompanying drawings.

In said drawings the reference-numeral 1 designates the silver souvenir-medal, which is octagonal in shape, its eight sides 2 being straight and flat. On each face and along the eight edges thereof is an ornamental border 3.

One face of the souvenir is ornamented with

a mountain scene 4 in cameo, consisting of 25 three mountain peaks 5, with a sunburst 6 at the apex of one mountain, a trestle-work 7 nestled in the valley between the mountains, and a mill 8 in the foreground. The entrance 9 to a mine is shown at the base of one of the 30 mountains, and mine-cars 10, a pack-mule 11, and a dray 12 appear in the foreground of the scene.

The reverse side of the souvenir is ornamented with a coat of arms 13.

35 My design presents a silver souvenir-medal of novel, pleasing, and attractive appearance.

Having thus described my invention, what I claim is—

The design for a souvenir-medal substantially as herein shown and described.

In testimony whereof I have hereunto set my hand in presence of two subscribing witnesses.

JOSEPH LESHER.
